UNITED STATES PATENT OFFICE

98,863

DESIGN FOR AN OVERALL BIB

Louis Jacobson, Birmingham, Ala., assignor to Liberty Overall Co., Birmingham, Ala., a partnership composed of Louis Jacobson and J.
Solomon

Application October 28, 1935, Serial No. 59,244

Term of patent 14 years

To all whom it may concern:

Be it known that I, Louis Jacobson, a citizen of the United States of America and resident of Birmingham, Alabama, U. S. A., have invented a new, original, and ornamental Design for an Overall Bib, of which the following is a specificcation, reference being had to the accompanying drawing, forming part thereof.

The drawing represents the bib showing my new design, the diagonal lines in the point of the inverted triangle on the pocket indicate a contrasting color.

I claim:—

The ornamental design for an overall bib as shown and described.

Dated at Birmingham, Alabama, this 24th day of Oct., 1935.

LOUIS JACOBSON.
